US00D955192S

(12) **United States Design Patent** (10) **Patent No.:** **US D955,192 S**
(45) **Date of Patent:** **** Jun. 21, 2022**

(54) **DRUM TOOL**

(71) Applicants: **Jose Reyes Ledesma**, Rosamond, CA (US); **Andrew Soehnlen**, California City, CA (US)

(72) Inventors: **Jose Reyes Ledesma**, Rosamond, CA (US); **Andrew Soehnlen**, California City, CA (US)

(73) Assignee: **JA Tooling LLC**, Council Bluffs, IA (US)

(**) Term: **15 Years**

(21) Appl. No.: **29/689,006**

(22) Filed: **Apr. 26, 2019**

(51) LOC (13) Cl. **08-05**

(52) U.S. Cl.

USPC **D8/21**; D8/29

(57) **CLAIM**

The ornamental design for a drum tool, as shown.

DESCRIPTION

FIG. 1 is the top view of the drum tool thereof,
FIG. 2 is the back view thereof,
FIG. 3 is the front view thereof,
FIG. 4 is the left view thereof,
FIG. 5 is the right view thereof,
FIG. 6 is the bottom view thereof; and,
FIG. 7 is the cross section view of FIG. 6 thereof.

1 Claim, 1 Drawing Sheet
